Patented Aug. 26, 1975

236,534

LAMP

Earl L. Mixon, 424 W. Peach St.,
Compton, Calif. 90222

Filed July 5, 1974, Ser. No. 485,907

Term of patent 14 years

Int. Cl. D26—05

U.S. Cl. D48—23 R

FIG. 1

FIG. 2

FIG. 3

FIG. 4

FIG. 5

FIG. 6

FIG. 1 is a perspective view of a lamp showing my new design;

FIG. 2 is an enlarged side elevational view of the lamp;

FIG. 3 is a second enlarged side elevational view of the lamp;

FIG. 4 is a third enlarged side elevational view of the lamp;

FIG. 5 is an enlarged top plan view of the lamp; and

FIG. 6 is an enlarged bottom plan view of the lamp. The chain is understood to have indeterminate length. I claim:

The ornamental design for a lamp, as shown and described.
